UNITED STATES PATENT OFFICE.

ROLF THELEN, OF MADISON, WISCONSIN, DEDICATED, BY MESNE ASSIGNMENTS, TO
THE PEOPLE OF THE UNITED STATES.

REVERSIBLE CIRCULATION INTERNAL FAN KILN.

Application filed April 19, 1924. Serial No. 708,323.

(GRANTED UNDER THE ACT OF MARCH 3, 1883; 22 STAT. L. 625.)

To all whom it may concern:

Be it known that I, ROLF THELEN, a citizen of the United States of America, and an employee of the Department of Agriculture, residing in Madison, Wisconsin (whose post-office address is Forest Products Laboratory, Madison, Wisconsin), have invented a new and Improved Reversible Circulation Internal Fan Kiln.

10 This application is made under the act of March 3, 1883, chapter 143 (22 Stat. 625), and the invention herein described and claimed may be used by the Government of the United States, its officers and em-

15 ployees, and by any person in the United States without the payment to me of any royalty thereon. I hereby dedicate the same to the free use of the Government and the people of the United States.

20 My invention consists in an improvement in the design of forced circulation kilns or chambers for drying and conditioning lumber or similar material. However, its use is not limited to wood or wood products. It

25 consists in the adaptation of fans of the disk type, or similar types, to the production of a unique internal circulation of air and the vapor in the kiln combined with the production and regulation of the heat and 30 the humidity within the kiln.

This invention is illustrated in Figures 1 to 3. Figure 1 represents a cross-sectional elevation. Figure 2 represents a horizontal section taken at various elevations below the 35 track level. Figure 3 represents a longitudinal sectional elevation of the fans and adjacent parts.

The principal feature which I claim as 40 novel and an improvement over existing kilns is the use and arrangement of the fans and the air distributing system. This arrangement is such that a very fast and uniform circulation of air and vapor through the piles of lumber may be secured

45 and it permits the periodic reversal of the direction of the air movement by simply reversing the direction of rotation of the fans. The air distributing system provides a very uniform flow of air throughout the 50 length and breadth of the kiln and eliminates the non-uniformity of drying, which is one of the commonest troubles experienced in the ordinary kiln. The arrangement of

the fans upon a shaft extending throughout the length of the kiln provides a simple 55 means of producing a brisk circulation; and the elimination of comparatively small ducts such as those used in external blower kilns reduces very materially the work required to produce a given circulation. The 60 differences in air pressure required in the operation of this kiln are much smaller than those ordinarily required in kilns employing centrifugal blowers, and the disk 65 fans operate very efficiently at these low pressures. Measurements recently made indicate that the static pressures necessary for the successful operation of this system are materially less than one-eighth of an inch 70 of water pressure. It is possible, therefore, by the use of this invention to produce a very great and uniform circulation of air and vapor within the kiln with a very small expenditure of power.

While it is obvious that there are many 75 possible ways in which the use of internal fans can be adapted to dry kilns of different types, this invention is limited to double track kilns in which the lumber is edge stacked. In edge stacked lumber the width 80 of each board is in a vertical direction, the thickness and length being in horizontal directions.

Any well-known means of heating the air 85 and the vapor in the kiln may be used in conjunction with this invention. When steam pipes are used they may be arranged beneath the lumber piles at the sides of the kiln or in any other convenient manner. Any convenient form and arrangement of 90 heaters may be used.

The drawings show and the specification describes steam jet pipes for increasing the humidity, and air inlet flues and air outlet flues with suitable dampers for decreasing 95 the humidity.

While the drawings show and the specification describes specific means for heating the air and the vapor in the kiln and for regulating the humidity of the air in the kiln, this invention is not limited specifically to the arrangements described, but may make use of any other well-known and suitable means for accomplishing the same purposes. While the drawings illustrate and 100 the specification describes certain specific 105

forms of piling, the invention is not limited to these particular forms since it is equally applicable to other forms; neither is the invention limited to the specific form of 5 rails, trucks, and track supports illustrated in the drawings and described in the specification.

Referring to Figures 1, 2, and 3, which are correspondingly lettered: AA represent the 10 side deflecting partitions. These partitions serve to form a passageway for the air from the heating coils to the fans and vice versa. BB are the fans producing the circulation. Straight-bladed disk fans are preferable. 15 Any type of fan, however, in which the reversal of the direction of rotation of the fan produces a reversal in the direction of the flow of the air current passing through the fan can be used. C is the shaft upon 20 which the fans are mounted. Provision is made to take care of the expansion and contraction of this shaft with changes in the temperature in the kiln and to take care of the thrust of the fans. This provision consists 25 in equipping one of the bearings II with suitable thrust rings or collars and equipping all of the other bearings II with any well-known means for longitudinal motion. Plain bearings and roller bearings require 30 no special provision of this kind. Certain types of ball bearings require housings which permit the entire bearings to slide longitudinally within them. DD are air inlet dampers used to regulate and control 35 the amount of air entering the kiln from the outside. EE are the heating coils. These may be of the return bend type or other convenient type. F is the steam jet pipe used to increase the humidity of the air in 40 the kiln. Suitable openings are provided to permit the escape of the steam throughout the length of the kiln. Various other common and well-known arrangements may be used. GG are the lumber-supporting 45 trucks. HH are the shaft hangers. II are bearings for the shaft C. JJ are the tracks upon which the lumber-supporting trucks run. KK are the side walls of the kiln. LL is the lumber to be dried. MM are the track 50 supports. N is the shaft pulley. OO are air outlet dampers for controlling the amount of air being exhausted from the kiln. P is a belt passing over the pulleys N and Q. Q is the motor pulley. R is the motor 55 which furnishes the power to drive the fans. S is the switch for controlling the speed and rotation of the motor armature. While the drawings show and the specification describes an electric motor, any other suitable 60 driving means may be used. TT are air inlet flues in which the dampers DD are fitted. UU are the air outlet flues in which the dampers OO are fitted. V is the central air passage. WW are the side air passages between the piles of lumber and the side

walls of the kiln. XX are the main air distributors. YY are the second diffusers. ZZ are the first diffusers. The plenum chambers between the second diffusers and the first diffusers are the secondary plenum 70 chambers. "aa" are the vertical deflecting ducts. "bb" are the fan housings and partitions. "cc" and "dd" are the plenum chamber partitions. While the drawings show and the specification describes certain 75 specific arrangement of the fans and shaft, this invention is not limited to this particular arrangement, since it is obvious that its functions can be performed in an equivalent manner with other arrangements of the fans. 80

The operation of the kiln is briefly as follows: The lumber is placed in the kiln, the doors and all of the dampers are closed, and the kiln is started. Steam is turned into the coils and the steam jets are turned on. Suitable regulating devices are provided to control and regulate the supply of steam to the heating coils and the supply of the steam to the steam jets. If it is found impossible to reduce the humidity to the desired point 90 with the steam jets all turned off, the dampers DD and OO are opened to allow fresh air to enter and moist air to escape. These dampers should be adjusted so that a humidity below that desired will be secured. 95 The steam jets may then supply a sufficient amount of steam to bring the humidity up to the desired point. Assuming that the direction of rotation of the fans is such that the air and vapor move upward through the lumber piles LL they will pass downward through the central air passage V, through the vertical deflecting ducts "aa", through the fans BB past the side deflecting partitions AA, over the heating coils EE through the two sets of diffusers ZZ and YY, and then upward through the lumber piles LL. When the direction of rotation of the fans is reversed the direction of the circulation of air and vapor is likewise reversed. When the direction of the circulation of the air and vapor is upward through the lumber the various chambers between the fans and the first diffusers and between the first diffusers and the second diffusers, respectively, are under slight pressure and act as plenum chambers. The velocity of the air movement through these chambers is comparatively slow. The use of these plenum chambers and the various sets of diffusers in the manner indicated produces a very uniform flow of air through the length of the kiln. The unbalancing effect of the horizontal air flow produced by the fans is practically eliminated by allowing a slight pressure to build up in the main air distributors. This is still further eliminated by the slight plenum in the space between the upper and lower distributors. It is obvious that the kiln would work reasonably well with single sets 100 105 110 115 120 125 130

of diffusers for each main air distributor and that still further uniformity in air distribution might be secured by adding a third or even a fourth set of diffusers. The principle, 5 of course, remains the same and practical expediency will determine the balance between increased uniformity of air distribution secured by the addition of more sets of distributors and the loss in efficiency which they 10 cause. It is also obvious that any well-known form of distributor may be used. The invention is not restricted to the form illustrated in which the openings consist simply of spaces between the slats running 15 the full length of the kiln. The air flow in the present invention differs materially from that in a single track edge stacked kiln because it is necessary to produce two separate and distinct air currents, one for 20 each side of the kiln. To accomplish this it is necessary to provide two sets of diffusers and two sets of plenum chambers, and to locate them at the sides of the fan instead of directly above it. It is necessary also to 25 modify the air distributing system by adding the vertical deflecting ducts. These ducts serve to eliminate longitudinal air movement when the direction of the circulation is upward through the central passage V.

30 When the direction of the circulation of the air and vapor is such that they pass through the diffusers and plenum chambers immediately after leaving the lumber piles instead of immediately before entering them, 25 the air distributing system, which consists of the main air distributor, the side deflecting partitions, the plenum chambers and the various diffusers, does not materially assist in producing a uniform circulation. The com- 40 paratively great length of travel from the fans to the point at which the air and vapor enter the lumber has been found sufficient to produce the desired uniformity in connection with the other features of the design.

45 The arrangement of the heating coils may be made to assist in smoothing out unevennesses in the circulation. It has been found through experience with a great many different types of forced circulation in dry kilns that it is not possible to secure uniformity of distribution of the air and vapor if they be handled at high velocities. In order to produce uniform satisfactory circulation, it is essential that the air and vapor 50 be moved at low velocities and that special means be provided for the uniform distribution of the air and vapor through the kiln. The use of internal fans and large plenum chambers produces this result, since the velocity of the air and vapor through the fans themselves is comparatively low and the velocity in the plenum chambers is so small that the velocity head can not be measured 55 with manometers and similar instruments with manometers and similar instruments 60 usually used for the purpose.

It is well understood that when the circulation of the air and the vapor in the kiln is continuously in one direction, that portion of the pile at which the air enters will dry more rapidly than the opposite side since 70 the air in its passage through the lumber picks up moisture and thus reduces its drying capacity. The reversal of the direction of the air circulation overcomes this defect since that edge of each lumber pile 75 which was the entering air edge before reversal becomes the leaving air edge after reversal. Those portions of the piles which dried fastest before reversal dry most slowly after reversal. The reversal of the circulation will in practice be done periodically 80 every two or three days or oftener, the exact period being determined by the condition of the lumber in the kiln.

Several arrangements of the plenum chambers are possible and practicable. The principal object of the plenum chambers and diffusers is to produce a uniform flow of air and vapor through the lumber to be dried, and any detailed arrangement which 90 will accomplish this result will be satisfactory if at the same time it does not consume an excessive amount of power.

Having fully described the principles of this invention and the manner in which 95 they can be embodied in a dry kiln, I claim as original:

1. In a double track dry kiln arranged for edge stacking: a series of fans; a shaft on which the fans are mounted for rotation; means for rotating said shaft in either direction to cause reversal of the circulation of the air and vapor in said kiln; and an air distributing system comprising side deflecting partitions, a main air distributor, vertical deflecting ducts, and two sets of diffusers. 10

2. In a double track dry kiln arranged for edge stacking: a series of fans; a shaft on which the fans are mounted for rotation; means for rotating said shaft in either direction to cause reversal of the circulation of the air and vapor in said kiln; dampered air inlet flues and dampered air outlet flues; and an air distributing system comprising side deflecting partitions, a main air distributor, vertical deflecting ducts, and two sets of diffusers. 11

3. In a double track dry kiln arranged for edge stacking: a series of fans; a shaft on which the fans are mounted for rotation; means for rotating said shaft in either direction to cause reversal of the circulation of the air and vapor in said kiln; dampered air inlet flues and dampered air outlet flues; means for heating the kiln and its contents; and an air distributing system comprising side deflecting partitions, a main air distributor, vertical deflecting ducts, and two sets of diffusers. 12

4. In a double track dry kiln arranged for 130

- edge stacking: a series of fans; a shaft on which the fans are mounted for rotation; means for rotating said shaft in either direction to cause reversal of the circulation of the air and vapor in said kiln; dampered air inlet flues and dampered air outlet flues; means for heating the kiln and its contents; means for humidifying the atmosphere in the kiln; and an air distributing system 10 comprising side deflecting partitions, a main air distributor, vertical deflecting ducts, and two sets of diffusers.
5. In a double track dry kiln arranged for edge stacking: a series of fans; a shaft 15 on which the fans are mounted for rotation; means for rotating said shaft in either direction to cause reversal of the circulation of the air and vapor in said kiln; a plenum chamber for each fan; and a diffuser 20 with restricted discharge passages for each plenum chamber.
6. In a double track dry kiln arranged for edge stacking: a series of fans; a shaft 25 on which the fans are mounted for rotation; means for rotating said shaft in either direction to cause reversal of the circulation of the air and vapor in said kiln; dampered air inlet flues and dampered air outlet flues; a plenum chamber for each fan; and a diffuser 30 with restricted discharge passages for each plenum chamber.
7. In a double track dry kiln arranged for edge stacking: a series of fans; a shaft 35 on which the fans are mounted for rotation; means for rotating said shaft in either direction to cause reversal of the circulation of the air and vapor in said kiln; dampered air inlet flues and dampered air outlet flues; means for heating the kiln and its 40 contents; a plenum chamber for each fan; and a diffuser with restricted discharge passages for each plenum chamber.
8. In a double track dry kiln arranged for edge stacking: a series of fans; a shaft on 45 which the fans are mounted for rotation; means for rotating said shaft in either direction to cause reversal of the circulation of the air and vapor in said kiln; dampered air inlet flues and dampered air outlet flues; means for heating the kiln and its 50 contents; means for humidifying the atmosphere in the kiln; a plenum chamber for each fan; and a diffuser with restricted discharge 55 passages for each plenum chamber.
9. In a double track dry kiln arranged for edge stacking: a series of fans; a shaft on which the fans are mounted for rotation; means for rotating said shaft in either direc- 60
- tion to cause reversal of the circulation of the air and vapor in said kiln; a series of plenum chambers for each fan; and a diffuser with restricted discharge passages for each plenum chamber.
10. In a double track dry kiln arranged for edge stacking: a series of fans; a shaft 65 on which the fans are mounted for rotation; means for rotating said shaft in either direction to cause reversal of the circulation of the air and vapor in said kiln; dampered air inlet flues and dampered air outlet flues; a series of plenum chambers for each fan; and a diffuser with restricted discharge 70 passages for each plenum chamber.
11. In a double track dry kiln arranged for edge stacking: a series of fans; a shaft 75 on which the fans are mounted for rotation; means for rotating said shaft in either direction to cause reversal of the circulation of the air and vapor in said kiln; dampered air inlet flues and dampered air outlet flues; means for heating the kiln and its contents; a series of plenum chambers for each fan; and a diffuser with restricted discharge 80 passages for each plenum chamber.
12. In a double track dry kiln arranged for edge stacking: a series of fans; a shaft 85 on which the fans are mounted for rotation; means for rotating said shaft in either direction to cause reversal of the circulation of the air and vapor in said kiln; dampered air inlet flues and dampered air outlet flues; means for heating the kiln and its contents; means for humidifying the atmosphere in the kiln; a series of plenum chambers for each fan; and a diffuser with restricted discharge 90 passages for each plenum chamber.
13. In a double track dry kiln arranged for edge stacking: a series of internal fans; a plenum chamber for each fan; and a diffuser with restricted discharge 95 passages for each plenum chamber.
14. In a double track dry kiln arranged for edge stacking: a series of internal fans; a series of plenum chambers for each fan; and a diffuser with restricted discharge 100 passages for each plenum chamber.
15. The herein described improvement in the art of drying lumber in a double track dry kiln arranged for edge stacking; which improvement consists in subjecting said lumber to a reversible circulation of air and vapor, said air and vapor passing in a substantially vertical direction through the lumber piles.

ROLF THELEN.
